UNITED STATES PATENT OFFICE

127,168

DESIGN FOR A GAME BOARD

Heber Hoge Clark, San Diego, Calif.

Application January 30, 1941, Serial No. 98,557

Term of patent 14 years

To all whom it may concern:

Be it known that I, Heber Hoge Clark, a citizen of the United States, residing at San Diego, in the county of San Diego and State of California, have invented a new, original, and ornamental Design for a Game Board, of which the following is a specification, reference being had to the accompanying drawing, forming part thereof.

I claim:

The ornamental design for a game board, as shown.

HEBER HOGE CLARK.
